UNITED STATES PATENT OFFICE.

JOHN F. O'CONNOR, OF CHICAGO, ILLINOIS, ASSIGNOR TO WILLIAM H. MINER, OF CHAZY, NEW YORK.

HIGH-CAPACITY SPRING-GEAR.

1,255,918.

Specification of Letters Patent.

Patented Feb. 12, 1918.

Application filed March 1, 1916. Serial No. 81,334.

To all whom it may concern:

Be it known that I, JOHN F. O'CONNOR, a citizen of the United States, residing at Chicago, in the county of Cook and State 5 of Illinois, have invented a certain new and useful Improvement in High-Capacity Spring-Gears, of which the following is a full, clear, concise, and exact description, reference being had to the accompanying 10 drawings, forming a part of this specification.

This invention relates to improvements in high capacity spring gears.

One object of this invention is to provide 15 a spring gear of higher capacity than those now in use and which may be employed in car constructions of standard design and sill spacing.

Another object of the invention is to provide 20 an efficient high capacity spring gear of relatively cheap construction, composed of few parts easily manufactured and assembled and disassembled.

The invention furthermore consists in improvements in the parts and devices and in the novel combinations of the parts and devices herein shown, described and claimed.

In the drawing forming a part of this specification, Figure 1 is a longitudinal, central vertical section of a draft rigging for 30 railway cars showing my improvement in connection therewith. Figs. 2 and 3 are transverse vertical sectional views of the structure illustrated in Fig. 1 and taken substantially on the lines 2-2 and 3-3 respectively. And Fig. 4 is an elevational view of one of the followers.

In said drawing, 10-10 denote draft members or center sills which in the form 40 shown comprise outwardly turned channels spaced the standard distance apart, to-wit, 12 $\frac{1}{8}$ inches. Secured to said draft members are rear stop lugs 11 and front stop lugs 12.

The draft gear proper comprises a front fol- 45 lower 13, rear follower 14 and three springs 15, 16 and 17, each of said springs, as usual, comprising an outer heavy coil 18 and an inner nested lighter coil 19. Each of the followers is provided on its inner face with 50 three bosses 20, 21 and 22, the same being located at the angles of an imaginary isosceles triangle with the upper boss 20 at the top of the triangle. The springs are seated on their respective bosses to maintain the

springs in proper position. The draw-bar 55 23 is operatively connected with the gear by means of a yoke designated generally by the reference A. As shown, the yoke A consists of a single arm having the cross section clearly illustrated in Fig. 3. The arm 60 of the yoke has an upstanding vertical web 24 and bottom outwardly extending flanges 25 and 26, the design being such that curved seats 27-27 are provided for the lower springs 16 and 17. The upper edge of the 65 vertical flange 24 is also curved as indicated at 28 to thereby form a seat for the spring 15. In order to lighten the yoke, the metal may be cut away as indicated at 29 on the underside. At the rear end, the yoke A is 70 provided with a vertical flange 30 which engages against the rear side of the follower 14, said flange being braced by ribs 31-31 at each side. At its front end, the yoke A is provided with a vertical wall 32 and on 75 the front thereof is provided a substantially rectangular pocket 33 in which is adapted to be received the butt of the draw-bar 23. The side walls of the yoke A at the front end are extended forwardly as indicated at 80 34-34, said walls being slotted to receive the transversely extending coupler key 35, which also extends through corresponding slots in the front lugs 12 and draft sills 10. As clearly shown in Fig. 4, each of the 85 followers is recessed on its lower face as indicated at 36 to correspond with and fit over the arm of the yoke. It will also be noted that fillets 37 are provided at the ends of the yoke between the horizontal arm 90 thereof and the vertical flanges 30 and 32, the followers being suitably curved to fit said fillets as indicated at 38-38. The yoke, 95 springs and followers are suitably supported by a saddle plate 39 bolted to the lower flanges of the draft sills and in order to prevent upward buckling of the spring 15, a suitable transversely extending plate 40 may be used, the same being riveted to the sills. As shown, each of the springs 15, 16 and 17 100 is of a well known commercial form 5 $\frac{1}{8}$ inches in outside diameter and of 35,000 lbs. capacity each. With the triangular arrangement of the springs, as shown, it is apparent that the springs, followers and yoke may 105 be placed in the space usually provided between sills 12 $\frac{1}{8}$ inches apart and having a depth of not over 12 inches, while at the

same time the capacity of the gear approximates 105,000 lbs. It will also be noted that the resultant force applied to the gear in either buff or draft is in a line $\frac{1}{3}$ of the 5 altitude above the horizontal base line of the imaginary triangle formed by the axes of the three springs which brings it within the vertical flange 24 of the yoke. In this way, the yoke is made exceedingly effective 10 and may be formed with a relatively small amount of metal. The gear is exceedingly compact while at the same time having a higher capacity than any spring gears heretofore on the market, so far as I am aware, 15 and which could be employed in car constructions of standard design and spacing. It is also obvious that the construction is relatively cheap to manufacture; the draw-bar and yoke may be readily disconnected by 20 moving the key 35; and the parts of the gear may be readily assembled and disassembled whenever necessary.

Although I have herein shown and described what I now consider the preferred 25 embodiment of my invention, the same is merely illustrative and I contemplate all changes and modifications that come within the scope of the claims appended hereto.

I claim:

30 1. In a railway draft rigging, the combination with a pair of draft sills spaced apart a predetermined distance and of a predetermined height, of three coiled springs each having the same diameter arranged in triangular 35 formation with one side of the formation extending horizontally, the length of said horizontal side corresponding substantially to said space between the sills and the height of the formation approximating the 40 height of the sills, the diameter of said springs being such that at least one spring

is in substantial tangential relation with the other two springs; followers at the ends of said spring; stops for said followers; and means for operatively connecting the 45 followers with a draw bar.

2. In a draft rigging, the combination with a pair of followers, of three springs extending between said followers, said springs being arranged in the form of a triangle, 50 and a yoke having a vertical flange and two horizontal flanges, said yoke extending beneath said springs.

3. In a draft rigging, the combination with a pair of followers, of three springs extending between said followers, said springs being arranged in the form of a triangle, and a yoke having a vertical flange and two horizontal flanges, said yoke extending beneath said springs, the resultant stress being in 60 line with said vertically extending flange of the yoke.

4. As an article of manufacture, a yoke for draft gears, said yoke comprising an arm having parallel spring seats on the upper face thereof with an intervening vertical flange, said yoke having upstanding flanges at each end thereof adapted to engage followers.

5. As an article of manufacture, a cast 70 yoke for draft riggings having a hooded forward end within which is adapted to be received a draw-bar butt, a horizontally extending single arm, the latter having an upstanding rear portion adapted to engage a 75 follower, said arm being provided with spring seats on the upper face thereof.

In witness that I claim the foregoing I have hereunto subscribed my name this 28th day of Feb., 1916.

JOHN F. O'CONNOR.
